(57) **CLAIM**

The ornamental design for bottle pump, as shown and described.

DESCRIPTION

FIG. 1 is a perspective view of a bottle pump.

FIG. 2 is another perspective view of the bottle pump.

FIG. 3 is a first side elevation view of the bottle pump.

FIG. 4 is a second side elevation view of the bottle pump, which is opposite to the first side elevation view of FIG. 3.

FIG. 5 is a third side elevation view of the bottle pump, which is adjacent to the first side elevation view of FIG. 3.

FIG. 6 is a fourth side elevation view of the bottle pump, which is opposite to the third side elevation view of FIG. 5.

FIG. 7 is a top plan view of the bottle pump; and,

FIG. 8 is a bottom plan view of the bottle pump.

The broken lines in the drawings represent unclaimed environmental subject matter and form no part of the claim.

1 Claim, 2 Drawing Sheets
